DESIGN FOR A SHOE HEEL

Lawrence E. Timberlake, South Portsmouth, Ky.,
assignor to Vulcan Corporation, Portsmouth,
Ohio, a corporation of Ohio

Application November 12, 1938, Serial No. 81,064

Term of patent 7 years

To all whom it may concern:

Be it known that I, Lawrence E. Timberlake, a citizen of the United States, residing at South Portsmouth, in the county of Greenup, State of Kentucky, have invented a new, original, and ornamental Design for a Shoe Heel, of which the following is a specification, reference being had to the accompanying drawing, forming a part thereof.

In the drawing,

Fig. 1 is a side elevation of the shoe heel showing my new design.

Fig. 2 is a perspective view of the shoe heel viewed from a position above and toward the front thereof.

Fig. 3 is a horizontal cross-sectional view taken on line 3—3, Fig. 1.

Fig. 4 is a central longitudinal section of the heel in a vertical plane.

I claim:

The ornamental design for a shoe heel, as shown.

LAWRENCE E. TIMBERLAKE.
